CLAIM

The ornamental design for a computer desk module, as shown and described.

DESCRIPTION

FIG. 1 is a top perspective view of a desk showing our new design; the broken lines indicate environmental structure and form no part of the claimed design;

FIG. 2 is a top plan view of FIG. 1;

FIG. 3 is a bottom plan view of the computer desk module;

FIG. 4 is a top plan view thereof;

FIG. 5 is a front elevational view thereof;

FIG. 6 is a rear elevational view thereof; and,

FIG. 7 is a left elevational view thereof, the right elevational view being a mirror image.
